SIMULATED FIRE HOOP FOR TOY VEHICLES OR THE LIKE

William R. Baynes and Harvey W. La Branche, Palos Verdes Peninsula, Calif., assignors to Mattel, Inc., Hawthorne, Calif., a corporation of Delaware

Filed Oct. 9, 1969, Ser. No. 19,483

Term of patent 14 years

Int. Cl. D21—02
U.S. Cl. D34—15

FIG. 1 is a front perspective view of a simulated fire hoop for toy vehicles embodying our design;

FIG. 2 is a rear perspective view of same; and

FIG. 3 is a front perspective view of same but here showing the simulated flames deflected outwardly in a manner similar to when a toy vehicle passes therethrough.

We claim:

The ornamental design for a simulated fire hoop for toy vehicles or the like, as shown and described.
